STEN E. B. SODERBERG, OF PASSAIC, NEW JERSEY, ASSIGNOR TO LESLIE COMPANY, OF LYNDHURST, NEW JERSEY

SIGNAL

Application filed February 29, 1932. Serial No. 595,859.

This invention relates to signal horns of the so-called tyfon type and particularly to such horns as applied to locomotives.

In connection with the description of the invention, reference is made to the accompanying drawing in which Fig. 1 is a vertical sectional view illustrating a horn of the type referred to applied to a locomotive and embodying my invention, and Fig. 2 is an enlarged view of a detail.

The horn proper is not modified in the use of my invention. It may briefly be described as follows: The body casting 1 has a passage 2 to the lower end of which steam or other operating fluid is admitted. The circular end 3 of the passage 2 bears against the resilient diaphragm 4. The space 5, surrounding the end portion of passage 2, opens to the atmosphere through the horn 6. The space 7 behind the diaphragm is closed except for its communication with the atmosphere through the small openings 8—8.

The admission of the fluid under pressure to operate the horn is controlled by means of the valve 9. This is operated in the usual way from the cab by means of a cord or rod attached at 10 at the upper end of the lever 11, this lever being pivoted at 12. The horn in the present instance is operated by means of steam from the boiler. The boiler sheet is shown at 13, 14 designating the steam space. Steam from the steam space reaches the valve by means of the passage 15.

The horn in the present instance is shown as comprising a steam jacket 16, the purpose of which is of course to heat the horn in the winter and keep it from freezing up and to prevent excessive condensation of steam in the operating portions. The steam jacket 16 receives its steam by means of the passage 17 branching off from the passage 15.

In locomotive whistles it is the usual practice to regulate the amount of steam supplied to the whistle by varying the distance to which the supply valve can be opened. To illustrate this, the ordinary way of regulating the amount of steam would be by screwing the stem 18 of the valve 9 into the yoke 19 by the desired amount. This evidently

fixes the distance 20 and thereby limits the distance to which the valve can be opened.

This is an objectionable practice inasmuch as the high velocity of the steam between the valve and its seat when the valve is opened to only a small amount, results in excessive cutting of the valve or its seat thereby causing the valve to leak.

I propose to regulate the amount of steam not by adjusting the distance to which the valve 9 opens but by further means next to be described. These means comprise a wall 21 between the steam inlet 15 and the valve 9, this wall being ported at 22. The port is of such size that it is capable of supplying a little more steam than is necessary for satisfactory operation of the horn and the amount of steam actually supplied is regulated by means of the valve 23. This valve is preferably given the form illustrated on an enlarged scale in Fig. 2. The tapered point 24 enters the orifice 22 more or less depending upon the setting, which is effected by means of the screw threads 25 working the corresponding screw threads in the plug 26, the valve being turned by means of the squared end 27 of the spindle 28, this squared end projecting out through the stuffing box 29. The stuffing box and valve are carried by the plug 26 which is screwed into the horn casting at 30.

In addition to the function spoken of, that is, the regulating of the amount of steam supplied to the horn, the valve 23 has the further function of serving as a shut-off valve when it is desired to shut off steam from the horn. For this purpose it has an annular seat 31 adapted to engage the seat 32 of the wall 21. It happens not infrequently that locomotive whistle valves are leaky, usually from the reason pointed out above. No shut-off valve is provided in the ordinary whistle and the valve remains leaky until the boiler is blown down and the valve can be ground in. By supplying such a shut-off valve as described above, it is possible to grind the valve 9 with steam on the boiler. It is merely necessary to turn the valve 23 until the annular seat 31 engages the seat on the partition 21 after which the plug 33 carrying with it the valve

9 can be screwed out and the valve ground on its seat to a tight fit. One advantage in the arrangement described is that in cold weather and with the locomotive in a place 5 where freezing temperatures prevail, the operating valve can be taken out for regrinding or other repairs while steam is still being supplied to the jacket of the horn, thereby keeping the horn from freezing up. The 10 shut-off valve 23, in other words, while closing off the steam from the passage controlled by the operating valve 9, leaves the passage 17 to the jacket open.

In the description given above it is assumed 15 that the whistle is to be operated by steam. Incidentally, Fig. 1 shows the connection 34 by means of which compressed air can be delivered to passage 2 to operate the horn. With this arrangement it is optional to blow 20 the horn either with steam or with compressed air.

In practice it is very convenient to make the base containing the valves separate from the horn proper. By doing this it is possible 25 to use the same sized base for different sizes of upper or horn section; and in addition the manufacture is simplified. The base has an inlet 15 for one fluid, a second inlet for a second fluid to which pipe 34 is connected, 30 and the common outlet for both fluids communicating with the passage 2 of the upper section; and in addition the base has the second outlet 17 for the first fluid communicating with the jacket.

35 What I claim is:

1. In apparatus of the class described, the combination of an audible fluid operated signal, a boiler, a conduit from the steam space of the boiler to the signal, a steam 40 jacket enclosing portions of the signal and communicating with the conduit, a valve controlling the conduit, a further valved conduit to supply a second operating fluid to the signal, adjustable means separate from said 45 first-named valve to regulate the rate of flow of the steam when the valve is open, and means between the valve and the boiler to shut off first named conduit.

2. In apparatus of the class described the 50 combination of a steam-operated horn, a steam jacket enclosing parts of it, a conduit to supply steam to the jacket, a second conduit branching off from the first one to conduct the steam for operating the horn, a shut-off valve controlling said second conduit, and a further conduit for a second operating fluid.

3. In apparatus of the class described the 60 combination of an audible fluid operated signal, a boiler, a conduit for operating steam from the steam space of the boiler to the signal, an operating valve controlling the conduit, means between the valve and the boiler for shutting off the conduit, a steam jacket 65 enclosing portions of the signal and com-

municating with the conduit at a point between the said means and the boiler, whereby the steam can be shut off from the signal and the valve repaired while steam is still supplied to the jacket to keep the signal from freezing up. 70

4. In apparatus of the class described, a horn base having two inlets for two separate operating fluids and a common outlet for them, a second outlet for one of the fluids and a shut-off valve to shut off the last-named fluid from the common outlet while leaving it free access to the single outlet. 75

5. In apparatus of the class described the combination of the horn base claimed in claim 4 with an upper horn section having an inlet for operating fluid and a jacket surrounding it, the jacket also having an inlet, the two inlets of the upper section being so arranged that when the base and upper section are assembled, the former inlet communicates with the common base outlet and the second inlet communicates with the second base outlet. 80 85

In testimony whereof I hereunto affix my 90 signature.

STEN E. B. SODERBERG.
